US00D965789S

(12) **United States Design Patent** (10) **Patent No.:** **US D965,789 S**
Al-Ali et al. (45) **Date of Patent:** **** Oct. 4, 2022**

(54) **BLOOD PRESSURE MONITOR**

(71) Applicant: **Masimo Corporation**, Irvine, CA (US)

(72) Inventors: **Ammar Al-Ali**, San Juan Capistrano, CA (US); **Chad A. DeJong**, Los Angeles, CA (US); **Valery G. Telfort**, Irvine, CA (US); **Kesu Wang**, Irvine, CA (US)

(73) Assignee: **Masimo Corporation**, Irvine, CA (US)

(**) Term: **15 Years**

(21) Appl. No.: **29/789,219**

(22) Filed: **Sep. 9, 2021**

Related U.S. Application Data

(63) Continuation of application No. 29/734,321, filed on May 11, 2020, now Pat. No. Des. 933,232.

(57) **CLAIM**

The ornamental design for a blood pressure monitor, as shown and described.

DESCRIPTION

FIG. 1 is a perspective view of a blood pressure monitor embodying our new design;

FIG. 2 is top view thereof;

FIG. 3 is bottom view thereof;

FIG. 4 is a side view thereof;

FIG. 5 is another side view thereof;

FIG. 6 is a front view thereof; and,

FIG. 7 is a back view thereof.

The broken lines illustrate portions of the patient monitor that form no part of the claimed design.

1 Claim, 4 Drawing Sheets
